UNITED STATES PATENT OFFICE.

ESREAL LOOKHOLTER, OF CHICAGO, ILLINOIS.

TIRE-CORE.

1,326,674.

Specification of Letters Patent. Patented Dec. 30, 1919.

Application filed August 3, 1918. Serial No. 243,105.

To all whom it may concern:

Be it known that I, ESREAL LOOKHOLTER, a citizen of the United States, residing at Chicago, in the county of Cook and State 5 of Illinois, have invented a new and useful Tire-Core, of which the following is a specification.

Heretofore, in the vulcanization of the casings of pneumatic tires, it has been customary to employ an inner core formed of rubber filled with compressed air. These cores were necessarily made and employed in various sizes so as to conform to the interior dimensions of the various sizes of tire-cases. 10 The fact that they were made of rubber—a material subject to constant deterioration by reason of the excessive heat to which they were subjected during the process of vulcanization—and requirement of numerous 15 sizes, rendered their use comparatively expensive.

My invention relates to an improvement upon such cores; and the objects I have in view are to substitute a metallic core for 20 that of rubber, thereby gaining in the matter of durability of the core, and to make the same expansible, so that, not only will one size of core answer for use in connection with more than one size of tire-case, 25 but, in any event, will yieldingly and firmly force the case being vulcanized outwardly 30 against the vulcanizer.

Other objects and advantages of the invention will hereinafter appear and the 35 novel features of the invention will be particularly pointed out in the claims.

Referring to the drawing:

Figure 1, is a side elevation of a tire-core embodying my invention, the same being 40 shown as closed and ready for insertion within a tire-case;

Fig. 2, is a vertical sectional view taken on the line 1—1 of Fig. 1;

Fig. 3, is a view similar to Fig. 2, but illustrating the core after the same has been inserted within the tire-case and expanded the desired degree; and

Fig. 4, is a view similar to Fig. 2, but illustrating a different means of expansion 50 from that shown in the remaining figures.

Similar numerals of reference indicate similar parts in all the figures of the drawing.

I propose to form the core, which in cross- 55 section approximates the interior of a tire, of the usual segmental shape and length as

heretofore, and preferably of sheet-metal of a sufficient gage to withstand the strains to which it will be subjected. In this instance, the core is formed of three longitudinal sections, namely, the bottom-section 1, and the two opposite side-sections 2, the latter being mere duplications. The meeting-edges of the bottom and side-sections 1 and 2, respectively, may be loosely connected below 60 the axis of the core and at one or more points in any desired manner so that the side-sections are capable of opening and closing. In the present instance, however, the metal of which the side and bottom-sections are formed is extended to form a central hinge-member 3 at each side of the core, the hinge-members at each side being connected by pintles 4.

Various means may be provided for expanding the core, which is accomplished by swinging the side-sections outwardly upon their hinges, in this instance, thus forcing the sides of the tire-case laterally against the vulcanizer. In Figs. 1, 2 and 3, of the drawings, the means employed for this purpose are expansion-springs 5, the same being coiled and supported at their opposite ends upon studs 6, projecting from the inner surfaces of the side-sections and therefore above 80 the hinges. These springs, it will be understood, are of sufficient strength for the purpose intended. Three of such are usually sufficient.

In Fig. 4 of the drawing, I have illustrated a form of core wherein the springs 5 are omitted, and the expansion of the side-sections is accomplished otherwise and more positively. In this latter construction, I employ a threaded post 7, securing the lower 95 headed end 8, by means of a clip 9, to the upper surface of the bottom section. The upper end of the post projects above the core through half-round openings 11, formed in the upper free meeting-edges of the side-sections and may terminate thereabove in a suitable operating-handle (not shown) or, in a squared head 12, adapted to receive a socket-wrench of the usual construction. Where expansion-springs are employed, as 100 in the construction of core first described, some means for locking the core closed are essential, and such may also be used in connection with the construction of core last described, if desired.

Any convenient means may be employed for this purpose, Figs. 1, 2 and 3, illustrat-

ing one simple means that I have found convenient and suitable. Lugs 12 and 13, respectively, are located at about the centers of the meeting-edges of the side-sections 5 2, and to the lug 12, is pivoted, as at 14, a U-shaped clamp 15 having a handle 16. When this handle is lowered, the opposing depending sides of the clamp embrace the two lugs 12 and 13, thus retaining the side- 10 sections together against the tendency of the springs. The core may now be inserted within the tire-case, after which the side-sections are unlocked and the said sections permitted to expand under the action of the 15 springs.

In the construction illustrated in Fig. 4, the sections may be held closed by hand or otherwise during the insertion of the core, and after the core is in place within the 20 tire-case the sides are expanded simply by rotating the threaded post 7. To accomplish this, the post 7 has threaded on it at any point above the hinges a nut 17, intended to bear against the inner sides of the two side- 25 sections and thus divide or expand said sections. In order to reduce friction and render the operation easier, I may journal small rollers 19, in the opposite ends of the nuts. It will be evident that as the post is rotated 30 to the left the nut will be fed upward and operating against the side-sections 2 will force the latter apart.

In operation, the core is first closed, and, if of the construction illustrated in Figs. 1, 35 2 and 3, the side-sections are locked against the tendency of the springs 5. Having been inserted at the desired point within the tire-case, the sides are then liberated and forced outward by the springs, or, as in the construction illustrated in Fig. 4, the post 7 is 40 rotated so as to feed the nut upward and thus spread the sides the desired degree.

Being formed wholly of metal, the core will not be affected by the heat of the vul- 45 canizing process, as heretofore, and being capable of expansion, one size of core will answer for several sizes of tire-cases, so that, on the whole, a considerable saving is the result.

50 It will be obvious that the core may consist of more than three sections or of only two, the principle involved being to con-

struct an expandible metal-core; also that the loose connections between the sections—hinges in this instance—may be altered in 55 construction and changed as to location; and likewise, various means may be substituted for locking the core against expansion and for accomplishing such expansion. While I very greatly prefer forming the 60 core of sheet-metal, yet it is possible to form the same of wood or any other material. I therefore do not wish to be understood as limiting my invention in respect to material.

Having described my invention, what I 65 claim is:

1. An arc-shaped tubular tire-core, comprising, a bottom and opposite side-walls or sections loosely connected to the bottom, and means for expanding said side-walls or sec- 70 tions.

2. An arc-shaped tubular tire-core, comprising, opposite expansible loosely connected side-walls or sections, means located above said loose connections for yieldingly 75 expanding said side-walls or sections, and means for securing said side-walls or sections when closed against expansion.

3. An arc-shaped tubular tire-core, comprising, opposite expansible side-walls or 80 sections, expanding-springs located between and bearing upon said side-walls or sections, and means for locking said side-walls or sections against such expansion.

4. An arc-shaped tubular tire-core, comprising, a bottom and opposite side-walls or sections, springs interposed between the side-walls or sections for expanding the same, means for securing the sections against expansion, and loose connections between the 90 bottom and the side-walls or sections.

5. An arc-shaped tire-core, comprising, opposite externally curved side-walls or sections and an intermediate bottom-section to which the side-walls or sections are loosely 95 connected, and means located between the side-walls or sections for expanding the same.

In testimony whereof I have signed my name to this specification in the presence of 100 a subscribing witness.

ESREAL LOOKHOLTER.

Witness:

W. S. DUVALL.
